UNITED STATES PATENT OFFICE

138,447

DESIGN FOR AN AIRPLANE HANGAR

Kenneth E. Van Scoy and Floyd B. Todd, Kansas City, Mo., assignors to Butler Manufacturing Company, Kansas City, Mo., a corporation of Missouri

Application June 9, 1944, Serial No. 113,934

Term of patent 14 years

(Cl. D13—1)

To all whom it may concern:

Be it known that we, Kenneth E. Van Scoy and Floyd B. Todd, citizens of the United States, residing at Kansas City, in the county of Jackson and State of Missouri, have invented a new, original, and ornamental Design for an Airplane Hangar, of which the following is a specification, reference being had to the accompanying drawing, forming part thereof, in which

Fig. 1 is a front perspective view of the hangar showing our design,

Fig. 2 is a rear perspective view showing our design.

We claim:

The ornamental design for an airplane hangar, as shown.

KENNETH E. VAN SCOV.
FLOYD B. TODD.
